DESIGN FOR A CRISPER PAN FOR A REFRIGERATOR CABINET

Oscar E. Norberg, Cincinnati, Ohio

Application November 16, 1948, Serial No. 149,646

Term of patent 14 years

(Cl. D44—1)

To all whom it may concern:

Be it known that I, Oscar E. Norberg, a citizen of the United States, residing at 2720 McKinley Avenue, Cincinnati 11, Ohio, in the county of Hamilton, have invented a new, original, and ornamental Design for a Crisper Pan for a Refrigerator Cabinet, of which the following is a specification, reference being had to the accompanying drawing, forming a part thereof.

In the drawing:

Fig. 1 is a top plan view of a crisper pan for a refrigerator cabinet, showing my new design;

Fig. 2 is a side elevation thereof;

Fig. 3 is a front elevation thereof;

Fig. 4 is a rear elevation thereof;

Fig. 5 is a sectional view taken along the line 5—5 of Fig. 1.

I claim:

The ornamental design for a crisper pan for a refrigerator cabinet, as shown.

OSCAR E. NORBERG.
